UNITED STATES PATENT OFFICE.

DONALD NOBLE, OF LEEDS, ENGLAND.

PORTABLE PUMPING APPARATUS.

SPECIFICATION forming part of Letters Patent No. 517,881, dated April 10, 1894.

Application filed March 8, 1892. Serial No. 424,217. (No model.) Patented in England August 26, 1890, No. 13,418; in France June 16, 1891, No. 214,211; in Belgium June 16, 1891, No. 95,292; in India October 7, 1891, No. 200, and in Austria-Hungary October 10, 1891, No. 41 and No. 2,951.

To all whom it may concern:

Be it known that I, DONALD NOBLE, a subject of the Queen of Great Britain, residing at Leeds, in the county of York, England, have invented new and useful Improvements 5 in Portable Pumping Apparatus, (for which I have obtained Letters Patent in England, No. 13,418, dated August 26, 1890; in France, No. 214,211, dated June 16, 1891; in Belgium, No. 95,292, dated June 16, 1891; in Austria-Hungary, No. 41 and No. 2,951, dated October 10, 1891, and in India, No. 200, dated October 7, 1891,) of which the following is a specification.

15 This invention relates to that class of portable pumping apparatus, such as is described in the specification accompanying my application for United States of America Letters Patent, Serial No. 405,852, filed September 16, 20 1891, and its object is to provide suitable 25 pedal mechanism (fixed to the outside of the water and other receptacle by joints at their toe ends) through a rocking lever armed with a lever fulcrumed on said shaft at or about its center, said lever being placed under the 30 pedals so that when one end of the pedal is depressed the opposite end of the lever and pedal resting upon it will be raised, or vice versa.

35 Figure 1 is a part sectional elevation; Fig. 2 a plan looking at the top.

Corresponding parts in the two views of the drawings are marked with the same letters of reference.

40 D, D' are skeleton pedals applied to the outer side of a bucket or water receptacle N (shown at Fig. 2. in dotted lines). In this bucket or water receptacle is (shown at Fig. 1) the outline of a horizontal pumping apparatus such as described in the above first 45 named specification. The pedals may or may not be armed on their upper surfaces with pieces of wood, cork or other non-conducting material d^x. In this arrangement the pedals 50 D D' are hinged at the toe or rear end d^{xx} to a skeleton stand or fixing M such as shown at Fig. 2, provided with lugs m, m' for the reception of bearing m², and a bearing m³, in which the shaft F revolvingly works. Protection is also made in the stand at m⁴ m⁴ for

the reception of the bucket or water receptacle N. On shaft P (which when a bucket is used passes within it) are mounted respectively without and within the receptacle a horizontal double ended lever O. and a vertical lever G''. The pedals D D' are supported at or about their centers by the lever O. The bracket or bearing m² may either be bolted directly to lugs m, m' or to the bottom of the bucket over the lugs so that the retaining bolts after passing through the bearing m² and bottom of the bucket may enter the lugs. The vertical lever G'' is employed for actuating the pistons whenever a rocking motion is imparted to the shaft F by the pedals. 65 At the point where the shaft F enters the bucket suitable packings such as india rubber and metal washers pressed against the inner side of the bucket by a helical spring on said shaft may be employed for making a 70 water tight joint. The valve box I connecting tubes H, H' inlet and outlet pipes i³ i⁴ to which flexible tubing may be attached are constructed as described in the said specification either at a little distance from the pump 75 barrel or close to it as shown in the drawings accompanying this specification.

By the above means motion is imparted to the pump pistons from the pedals which are hinged to the framing, through a rocking 80 shaft armed with a lever fulcrumed on said shaft at or about its center, said lever being placed under the pedals so that when one end of the pedal is depressed the opposite end of the lever and pedal resting upon it will be 85 raised or vice-versa.

Having now particularly described and ascertained the nature of my said invention and in what manner the same is to be performed, I declare that what I claim is—

90 A portable pumping apparatus, consisting of a stand M; a water receptacle N; a pump within said receptacle; the shaft F passing through the walls of said receptacle; bearings for said shaft on the stand M, within and 95 without the receptacle; the vertical lever G'' connected rigidly with said shaft F and within said receptacle and engaging with the piston rod of said pump; the levers O, O, rigidly connected with said shaft F, outside of said re- 100

ceptacle; the pedals D, D' pivoted at their forward ends to the frame M, adjacent to the side of said receptacle N, and arranged at an angle to each other, whereby the said pedals 5 D, D', will bear approximately at right angles, substantially as described.

In testimony whereof I have hereunto

signed my name to this specification in presence of two subscribing witnesses.

DONALD NOBLE.
